UNITED STATES PATENT OFFICE.

FREEBORN F. RAYMOND, 2d, OF NEWTON, MASSACHUSETTS.

DESIGN FOR A BALL MEMBER FOR FASTENERS FOR GLOVES.

SPECIFICATION forming part of Design No. 25,117, dated February 4, 1896.

Application filed November 21, 1894. Serial No. 529,531. Term of patent 14 years.

To all whom it may concern:

Be it known that I, FREEBORN F. RAYMOND, 2d, a citizen of the United States, residing at Newton, in the county of Middlesex and State 5 of Massachusetts, have invented and produced a new and original Design for the Ball Member of Fasteners for Gloves, &c., of which the following is a specification, reference being had to the accompanying drawings, forming a part of this specification.

In the drawings, Figure 1 is a view in perspective of the ball member of a fastener for gloves, &c., having the features of my invention. Fig. 2 is a view in elevation, and Fig. 5 3 is a view in plan thereof. Fig. 4 is a view in longitudinal section. Fig. 5 is a view in cross-section upon the dotted lines of Fig. 2.

The ball has the rounded top *a*, the flange *b*, the neck *c*, and the outwardly-curved section *c'* between the neck and the top, with 20 interposed V-shaped depressions *c²*, oval in form, upon their outer edges.

Having thus fully described my invention, I claim and desire to secure by Letters Patent of the United States—

25

The design for the ball member of fasteners for gloves or other articles herein shown and described.
